Filed Aug. 18, 1965, Ser. No. 86,619

Term of patent 14 years

(Cl. D9—2)

Fig. 2.

Fig. 3.

Fig. 4.

Fig. 5.

FIGURE 1 is a perspective view of an applicator for drying-cleaning rugs and the like showing my new design; FIGURE 2 is a top plan view thereof;

FIGURE 5 is an elevational view of one side of the applicator, the opposite side being of the same appearance.

The dominant features of my design reside in the portions shown in solid lines, the handle of the applicator being shown fragmentarily in phantom for illustrative purposes only.

I claim:

The ornamental design for an applicator for drying-cleaning rugs and the like, substantially as shown and described.
